UNITED STATES PATENT OFFICE.

EDWARD WYSKOSKY, OF WILMINGTON, DELAWARE.

UMBRELLA.

1,104,598.

Specification of Letters Patent. Patented July 21, 1914.

Application filed September 30, 1913. Serial No. 792,678.

To all whom it may concern:

Be it known that I, EDWARD WYSKOSKY, a subject of the Emperor of Austria-Hungary, residing at Wilmington, in the county 5 of Newcastle and State of Delaware, have invented certain new and useful Improvements in Umbrellas, of which the following is a specification, reference being had therein to the accompanying drawing.

10 This invention relates to umbrellas and has for its object to provide an article of such class, in a manner as hereinafter set forth, with means for reducing to a minimum the liability of the blowing of the 15 umbrella cover wrong side out by sudden gusts of wind.

A further object of the invention is to provide an umbrella with foldable ribs, each rib consisting of two sections and the 20 lower rib sections having associated therewith, means to assist in opening the umbrella cover when the stretchers are being shifted to open position.

25 A further object of the invention is to provide an umbrella having its ribs formed of sections the lower rib sections having associated therewith means for maintaining them extended.

With the foregoing and other objects in 30 view the invention consists of the umbrella construction, combination and arrangement of parts as hereinafter more specifically described and illustrated in the accompanying drawing wherein is shown an embodiment of the invention, but it is to be understood that changes, variations and modifications can be resorted to, which fall within 35 the scope of the claim hereunto appended.

In the drawings wherein like reference 40 characters denote corresponding parts throughout the several views, Figure 1 is an elevation of an umbrella stick showing the adaptation therewith of a rib and stretcher constructed in accordance with this invention, the rib being in an extended position, Fig. 2 is an elevation illustrating the rib 45 folded and further illustrating the sections of stick disassembled, Fig. 3 is a sectional detail illustrating the upper rib section and 50 stretcher, Figs. 4 and 5 are details illustrating the position of the outer end of the stretcher in the upper rib section, and Fig. 6 is a detail, broken away, of the sectional rib.

Referring to the drawings in detail the stick 55 comprises a handle section 7, an intermediate section 8, a tip section 9, a notch 10 carried

by the intermediate section 8, a handle 11 upon one end of the section 7, a spring catch 12 carried by the intermediate section and a runner 14 is slidingly mounted upon the sections 7 and 8 and which, when the umbrella is open, is engaged by the catch 12. The handle section 7 is detachably connected to the intermediate section 8 as at 13, and the tip section 9 is detachably connected to the 60 intermediate section 8 as at 15. Each of the ribs of the umbrella includes an upper section 16 and a lower section 17, the latter being foldable outwardly and upon the section 16. The section 16 has its upper terminus 65 reduced as at 18 and provided with an opening 19 through which extends the ordinary coupling means for connecting the section 16 to the notch 10. The section 16 is furthermore provided with a reduced lower 70 portion 20 having an opening 21 and between the portions 18 and 20 the section 16 is enlarged and is substantially inverted U-shaped. The said enlarged portion is indicated at 22 and is formed near its upper 75 terminus with inwardly extending flanges 23 and an outwardly extending stock 24. Arranged within the portion 22 in the lower terminus is a block 25, provided with a seat 26, and an incline surface 27. Secured within said portion 22 is a pair of holding springs 28, each of the latter has its upper end supported by the flange 23 and fixedly secured to the portion 22, as at 29. The lower ends of springs 28 are enlarged and oppose the 80 seat 26. The function of the springs 28 will 85 be presently referred to.

The lower section 17 of each rib has depending therefrom a pair of eyes 30 and 31 which constitute guides for a spring controlled holding arm 32. One of the eyes 30 provides an abutment for one end of a coil spring 33, the latter surrounds the rod 32, and has one end connected to the rod 32, as at 34. The lower rib section 17 is pivotally connected as at 35 between the arms 36, of a support 37. Extending through the opening 21, of the lower terminus 20, of the rib section 16, is a pin 38, for pivotally connecting the lower end of the rib section 16 95 to the arms 36. The rod 32 extends between the arms 36 and beyond the pivot 35. The rod 32 has its inner end formed with an eye 39, to which is connected a flexible pulling member 40.

100 The reference character 41 denotes a stretcher, which has one end pivotally con-

nected to the runner 14 and its other end provided with a tubular head 42 which, when the rib is extended, is mounted in the seat 26, and maintained against seat 26, by 5 the holding springs 28. When the rib is folded, the head 42, rides up the section 16, until it is arrested by the stock 24. The holding springs have a rounded portion, which assists in maintaining the head 42, 10 against the seat 26. The stretcher 41 intermediate its ends is provided with an opening 43, through which extends the flexible member 40, the latter having its other end, as at 44, attached to the upper portion 15 of the section 16 of the rib.

When the stretcher 41 is extended, the member 40 is taut, and under such circumstances the member 40 will pull upon the rod 32, against the action of the spring 33 20 whereby the section 17 is maintained extended. When the stretcher 41 is lowered, the member 40 becomes slack, and the section 17 can be folded back upon the section 16. When the spreader 41 is shifted to open 25 the rib, the action of the stretcher upon the member 40, will cause said member 40, to

pull the rod 32, and assist in shifting the section 17 to open position. The member 40, rod 32 and spring 33 assist in preventing the ribs from being blown outwardly by 30 sudden gusts of wind.

What I claim is:—

An umbrella comprising a stick, a runner slidably mounted thereon, a stretcher pivotally connected to the said runner, a rib 35 formed of an upper and lower section, said stretcher slidably mounted on the upper rib section, resilient members carried by said upper section and engaging said stretcher for maintaining the latter extended when 40 the umbrella is open, a spring actuated rod carried by said lower section, and means connected to the upper section and to said rod and engaged by the stretcher for pulling the rod to maintain the lower section 45 extended.

In testimony whereof I affix my signature in the presence of two witnesses.

EDWARD WYSKOSKY.
